UNITED STATES PATENT OFFICE.

MAX NOVICK, OF NEW YORK, N. Y.

BED-SPRING.

1,329,202.

Specification of Letters Patent. Patented Jan. 27, 1920.

Application filed June 20, 1919. Serial No. 305,502.

To all whom it may concern:

Be it known that I, MAX Novick, a citizen of the United States, and a resident of the city of New York, borough of the Bronx, in the county of Bronx and State of New York, have invented a new and Improved Bed-Spring, of which the following is a full, clear, and exact description.

This invention relates to adjustable beds 10 and particularly to adjustable bed springs or frames.

Among the objects of the invention is to provide a combined bedstead and spring having adaptability for adjustment longitudinally and laterally to accommodate the mechanism for large persons or to reduce the size thereof to economize space if the bed is to be occupied by small persons.

Another object of the invention is to provide a novel means for maintaining the symmetry and effectiveness of the head and foot pieces of the bed with respect to the handling thereof in the various positions of adjustment.

25 With the foregoing and other objects in view the invention consists in the arrangement and combination of parts hereinafter described and claimed, and while the invention is not restricted to the exact details of 30 construction disclosed or suggested herein, still for the purpose of illustrating a practical embodiment thereof reference is had to the accompanying drawings, in which like reference characters designate the same parts 35 in the several views, and in which—

Figure 1 is a plan view, partially in horizontal section, indicating my improvement.

Fig. 2 is a vertical transverse section on the line 2—2 of Fig. 1.

40 Fig. 3 is a partial longitudinal section on the broken line 3—3 of Fig. 1; and

Fig. 4 is a vertical sectional detail on the line 4—4 of Fig. 2.

Referring now more specifically to the 45 drawings I show a bedstead comprising a head 10, a foot piece 11 and a spring 12. The head and foot pieces 10 and 11 may be of any suitable design and so far as the invention is concerned are preferably substantially alike. Each of these pieces includes corner posts 13 shown as made of tubular metal and rectangular in cross section. Between each pair of corner posts extend horizontal bars 14 which are telescopic 50 for adjustment of the corner posts toward and from each other so as to vary the width

of the bed. The outer tubular members 14^a of the bars are provided with a plurality of upright rods 15, or their equivalent, constituting rigid bracing connections between 60 the sleeve members 14^a and are fixed in position with respect thereto and one another.

As indicated best in Fig. 1 the inner members 14^b are of tubular construction and have along their upper sides longitudinal slots 16 65 in and along which the headed ends 17 of auxiliary rods 18 are fitted and adapted to slide, from the post to which the members 14^b are secured out toward the center of the bed or toward the opposite post so as to fill 70 the gap that would otherwise be left when the head or foot panels of the bed are elongated or widened. The free ends of the outer members 14^a are notched at 19 along their faces to accommodate the auxiliary 75 rods 18, especially when the bed is collapsed at which time the rods 18 may all be received in the notches when they are all adjusted close to the adjacent post. By providing for the movable or adjustable rods 80 18 I am able to produce a design of a bed that remains substantially symmetrical in all positions of adjustment.

The bed spring 12 comprises side rails 20, end rails 21 and intermediate transverse 85 rails 22 and any suitable design or construction of woven spring fabric 23.

The side rails 20 each comprise an outer member 20^a and an inner telescopic member 20^b. The ends of these side rails 20 are supported upon socket members 24 at the corner posts as usual. The transverse rail 21 at the head of the bed comprises two telescopic outer and inner members 21^a and 21^b and one of the intermediate transverse rails 22 95 is composed of similar telescopic members 22^a and 22^b, the outer ends of which are connected to the free ends of the side members 20^a while the outer ends of the members of the rail 21 at the head are connected 100 to the head ends of the rail 20^a. To these several members are connected two spring sections 23^a and 23^b which constitute a rectangular spring section of fixed length and variable width. The width may be fixed 105 after adjustment by means of bolts with winged nuts or the like acting through registering slots 26 in the telescopic rails 21 and 22.

The rail 21 at the foot of the bed is connected to the telescopic members 20^b of the side rails to whose free ends are connected 110

the two parts of the rail 22 farthest from the foot and to these members are attached spring sections 23^c and 23^d forming spring sections of fixed length but of variable width, the width of which may be fixed and made permanent by means of the bolts 25 as above described. This locking of the adjustable spring members will serve naturally to fix the adjustment of the main bed frame.

10 I claim:

1. In a bedstead of the character set forth, the combination of head and foot pieces of variable length, each of said pieces comprising members having fixed spaced rods, and auxiliary rods parallel to the fixed rods and adjustable along the head and foot pieces to retain symmetry of spacing in all adjustments of said head and foot pieces.

15 2. In an adjustable bedstead, the combination of head and foot pieces each com-

prising a vertical post and horizontal telescopic rails connected thereto, each rail having outer and inner telescopic members, a series of vertical rods fixed at their upper and lower ends to the outer telescopic members, and a series of auxiliary rods parallel to the fixed rods and movable toward and from the fixed rods and one another.

20 3. In an adjustable bed, the combination of head and foot pieces each having parallel telescopic rails, the inner members of the rails having longitudinal slots and the outer members of the rails having at their free ends notches registering with the slots, a series of fixed rods connected to the notched members of the rails, and a series of auxiliary rods fitted and movable in said slots and adapted to nest in said notches when the end pieces are collapsed.

MAX NOVICK.
